UNITED STATES PATENT OFFICE.

LANDON H. STEPHENSON, OF RICHMOND, VIRGINIA.

SAFETY-RAZOR.

1,116,750.

Specification of Letters Patent. Patented Nov. 10, 1914.

Application filed October 18, 1913. Serial No. 795,995.

To all whom it may concern:

Be it known that I, LANDON H. STEPHENSON, a citizen of the United States, residing at Richmond, in the county of Henrico and 5 State of Virginia, have invented certain new and useful Improvements in Safety-Razors, of which the following is a specification.

This invention relates to a safety razor and the principal object of the invention is 10 to provide a safety razor having an improved type of holding frame which is so constructed that the various parts will be securely held in the desired position when the blade is placed in the frame.

15 Another object of the invention is to so construct the frame that the blade will be prevented from slipping after being put in place and to also so construct the frame that the blade guard cannot move from a set 20 position upon the blade.

Another object of the invention is to so construct the frame that the blade can easily be put in place or removed.

This invention is illustrated in the accompanying drawings wherein:—

Figure 1 is a side elevation of the improved razor in a closed position; Fig. 2 is a side elevation of the razor in an open position; Fig. 3 is a plan view of the razor; Fig. 4 is a plan view of the blade; Fig. 5 is a transverse section taken along the line 5—5 of Fig. 1; and, Fig. 6 is a side elevation of the clip which holds the blade. Fig. 7 is a transverse sectional view taken along the 35 line 2—2 of Fig. 1.

The supporting plate 10 which forms the body portion of the frame is provided at one end with the hinge-ears 11 and has its opposite end portion formed into a handle 12 upon which there is pivotally mounted 40 the U-shaped member 13. This body portion is crimped intermediate its length to form the seat 14 which forms a rest for the clip, to be hereinafter described, and carries pivot ears 15 which extend beyond the thickness of the handle 12. A clamp 16 which is formed from an elongated strip of material is pivotally mounted between the hinge-ears 11 and has its free end portion crimped to form an offset portion 17 which is clearly shown in Fig. 1. The end 50 of the clamping strip fits into a cut out portion formed in the handle 12 and is held in the closed position by a sleeve 18 which is 55 slidably mounted upon the handle.

A clip 19 is pivotally mounted between

the pivot ears 15 upon the pivot pin 20 and is intended to removably engage the razor blade. This clip is formed from a single strip of resilient material which is bent 60 intermediate its length to form the two jaws 20. One of these jaws 20 carries a pin 21 and the other jaw is provided with a pressed out pocket 22. This pin and pocket serve to prevent the razor blade from moving 65 pivotally between the two jaws.

The razor blade 23 is provided with a neck 24 which fits between the jaws of the clamp 19 and is provided with a notch 25 to engage the pin 21 and with a bead 26 70 which fits into the pocket 22. The outer end portion of the blade is provided with wings 27 which extend upon opposite sides of the hinge-ears 11 so that transverse movement of the blade upon the body portion 10 75 will be prevented. Pins 28 are carried by the body portion and pass through the openings 29 formed in the blade so that when the blade is resting upon the body portion with the pins passing through the openings 80 and the wings 27 positioned upon opposite sides of the hinge-ears, it will be impossible for the blade to move either longitudinally or transversely.

A guard 30 is provided with a neck 31 85 which fits into a socket piece 32 pivotally mounted between the pivot ears 15. The side jaws of this socket piece 32 pass upon opposite sides of the clip 19 as shown in Fig. 5 so that when the guard is in the closed 90 position independent transverse movement between the guard and clip 19 will be prevented. This guard 30 rests flat against the central portion of the blade 23 with the pin 28 passing through openings formed in the 95 guard and it will thus be seen that the pins 28 not only prevent transverse and longitudinal movement of the blade, but also prevent movement of the guard. The side portions 33 of the guard are bent as shown 100 in Fig. 2 and are slotted to form teeth as shown in Fig. 1 so that the blade 23 may cut properly. It is, of course, obvious that any other shape of guard which will fit the razor and clip could be used in place of the 105 one shown.

When this razor is to be used, the securing strip 16 is first opened and the guard and clip are then raised so that the razor blade can be connected with the clip and 110 then swung down upon the body portion 10. The guard is then swung downwardly upon

the blade and the securing strip 16 is pressed flat against the guard and handle 12 so that the securing sleeve 18 can be moved across its free end. The frame, guard, and securing strip, can be formed of any suitable material such as sheet metal but it is desired to have the securing strip slightly resilient so that when the sleeve 18 is in the locked position, the securing strip will hold the sleeve in place by frictional engagement and thus the sleeve prevented from slipping out of a locked position when the razor is in use. After the razor has been used, the sleeve 18 is moved to release the clamping strip and this can then be raised to an open position so that the guard can be raised and the blade removed from the clip 19. The various parts of the razor can then be thoroughly cleaned and also removed and can then be again put together and put away for safe keeping. A razor has therefore been provided which is very simple in construction and is so constructed that the blade and guard will be securely held in the desired position when the razor is in use.

If it is desired to strap the blade, the blade is moved to one side of the longitudinal center of the frame with the pins 28 passing through the openings 29 formed in the side portions of the blade instead of the openings 29 in the center of the blade. The cutting edge of the blade will then extend beyond the plate 10 a sufficient distance to permit it to engage a strap. The guard will be removed when stropping the blade.

What is claimed is:

1. A razor comprising a body portion having one end portion constituting a handle, pivot ears extending from said body portion adjacent the handle, a clip pivotally connected with said pivot ears, a blade removably connected with said clip and resting against said body portion, pins carried

by said body portion and passing through 41 openings formed in said blade, hinge ears at the outer end of said body portion passing through a slot formed in said blade, a guard pivotally connected with said pivot ears and engaging said blade, said guard being provided with openings through which said pins pass, and a clamp strip pivotally mounted between said hinge ears and extending along said guard with its inner end removably connected with said handle. 51

2. A razor comprising a body portion, a handle at one end of said body portion, a blade engaging clip pivotally connected with said body portion, hinge ears at the outer end of said body portion, a guard 60 pivotally connected with said body portion to engage a blade, a clamp strip pivotally connected with said hinge ears and extending along said guard, and means carried by said handle for releasably engaging the 65 free end portion of said clamping strip.

3. A razor comprising a body portion, pivot ears carried by said body portion, a clip pivotally connected at said pivot ears, said clip being formed from a single strip 70 of resilient material bent intermediate its length to provide clamping jaws, one of said jaws being provided with a blade engaging pin and the other jaw provided with a pocket, a blade provided with a neck 75 extending between the clamping jaws of said clip and provided with a notch engaging said pin and with a bead fitting into said pocket, a guard for engaging said blade, and a clamping strip for engaging 80 said guard to hold the same in engagement with said blade.

In testimony whereof I affix my signature in presence of two witnesses.

LANDON H. STEPHENSON.
